UNITED STATES PATENT OFFICE.

HENRY TEXTOR, OF BROOKLYN, NEW YORK.

DESIGN FOR A NEWEL-POST.

SPECIFICATION forming part of Design No. 14,943, dated April 1, 1884.

Application filed January 2, 1884. Term of patent 7 years.

To all whom it may concern:

Be it known that I, HENRY TEXTOR, of Brooklyn, in Kings county and the State of New York, have invented and produced a certain new Design for Newel-Posts, of which the following is a specification.

I will describe in detail a newel-post embodying the design, and then point out the features in claims.

10 The accompanying illustration is a perspective view of a newel-post embodying the new design.

The base *a* of this newel-post is of polygonal form. It is surmounted by a body, the lower 15 portion of which consists of a large convex molding, *b*. Above this large molding *b* is a concave molding, *c*. Above the molding *c* is an outwardly-flaring portion, *d*, divided longitudinally by grooves *d'*. Immediately above 20 this flaring portion *d* is a flat polygonal portion, *e*. Above this is an angular groove, *f*. Next above this groove *f* is a long upwardly- 25 tapering portion, *g*. The flat polygonal portion *e* has on its several sides a square or diamond-shaped ornament, *h*, which projects over the adjacent outwardly-flaring portion *d*, and also over the long upwardly-tapering portion *g*. The long upwardly-tapering portion has scroll-shaped ornaments *i* on the upper portion, small scroll-shaped ornaments *j* on the lower portion, and grooves *k* and *l* between the scroll-shaped ornaments. On the upper part 30 of the long tapering portion *g* is a molding, *m*. Above this molding is a portion, *n*, and 35 surmounting moldings *o*. Above the moldings

o are gable-like projections *p*, having a curved outline and recessed ornaments. Above these gable-like projections is a foliate molding, *q*. The finial of this newel has a polygonal base, *r*, a concave molding, *s*, above the base, a cylindrical portion, *t*, embellished with shield-like ornaments *u* and intermediate scallops, a conical upper portion, *v*, provided with radial grooves or stria, and a surmounting button, *w*.

What I claim as my design, and desire to secure by Letters Patent, is—

1. In a design for a newel post, the body thereof, consisting of the convex molding *b*, the concave molding *c*, the portion *d*, having the longitudinal grooves *d'*, the flat portion *e*, 50 the angular groove *f*, the tapering portion *g*, the diamond-shaped ornament *h*, the scroll-shaped ornaments *i* and *j*, the grooves *k* *l*, the molding *m*, the portion *n*, the surmounting molding *o*, the gable-like projections *p*, and 55 the foliate molding *q*, substantially as described and shown.

2. In a design for a newel-post, the finial thereof consisting of the polygonal base *r*, the concave molding *s*, the cylindrical portion *t*, 60 shield-like ornaments *u* and intermediate scallops, the conical upper portion, *v*, and the surmounting button *w*, substantially as described and shown.

3. In a newel-post, a body made and ornamented substantially as described and shown.

HENRY TEXTOR.
